C. A. HUSSEY.
DYNAMO ELECTRIC MACHINE.

No. 249,241.

Patented Nov. 8, 1881.

UNITED STATES PATENT OFFICE.

CHARLES A. HUSSEY, OF NEW YORK, N. Y., ASSIGNOR TO THE HUSSEY ELECTRIC COMPANY OF NEW YORK.

DYNAMO-ELECTRIC MACHINE.

SPECIFICATION forming part of Letters Patent No. 249,241, dated November 8, 1881.

Application filed March 22, 1881. (No model.)

To all whom it may concern:

Be it known that I, CHARLES A. HUSSEY, of the city of New York, in the county and State of New York, have invented certain new and useful Improvements in Dynamo-Electric Machines, of which the following is a specification.

The object of my invention is to produce a simple and desirable armature for a dynamo or magneto electric machine.

My armature is composed of a hollow body or core and hollow radial extensions communicating with the interior of the body and furnished with connected coils of wire. A circulation of air will be maintained through the body or core and extensions of the armature when it rotates, and will serve to keep it cool.

In the accompanying drawings, Figure 1 is a plan of an armature embodying my improvements, and a commutator therefor. Fig. 2 is a diagrammatic view comprising a transverse section of the armature, a perspective view of a commutator therefor, and the wires leading from the armature; and Fig. 3 is a plan of the armature with the coils of wire on its extensions differently connected, and a number of commutators therefor.

Similar letters of reference designate corresponding parts in all the figures.

A designates a cylindrical body or core, which is hollow from end to end, and may be made of wrought-iron or any other suitable material.

B designates a number of radial extensions, which consist of tubes of similar material, screwed into or otherwise secured to the body or core A, made open from end to end, and communicating with the interior of the said body or core. On these radial extensions are coils of wire E E', &c., which are wound in the form of inverted frusta of cones, or, in other words, in the form of frusta of cones arranged with their smaller ends next the body or core A. These coils are wound in the form described, so that they will fit close together circumferentially around the body or core, and hence so that the greatest possible amount of wire may be employed in the least possible space. At the outer ends they also fit closely

together lengthwise of the body or core. These 50 radial extensions B are arranged in circular rows and in line lengthwise of the body or core. The coils of wire on the radial extensions may be wound on any suitable contrivance, and slipped over the radial extensions 55 after being wound. When this armature rotates the outer end of these radial extensions are intended to travel in close proximity to the field-magnets of a dynamo or magneto electric machine, so that currents of electricity will be 60 generated in the coils of wire on the said radial extensions. The coils of wire on said radial extensions may be connected in various ways, as hereinafter more particularly explained. As here shown, there are eight of 65 these radial extensions in each row around the body or core of the armature, and eight arranged in line lengthwise of the same.

To each end of the body or core A of the armature there is fitted a disk or end plate, C. 70 A shaft, D, extends through these disks, and its ends protrude beyond the disks and form journals, on which the armature rotates. As shown, these disks have flanges a, which enter the body or core A, and are secured in 75 place by screws b, entering the ends of the body or core, so as to be interlocked positively therewith, to turn therewith. These disks may have openings for the admission of air, and the air entering these openings will, as the 80 armature rotates, be carried into the body or core, and will pass thence to and out of the radial extensions, thus keeping the armature cool.

On one of the journals of the armature shown 85 in Fig. 1 is a commutator, F, which, as here shown, is intended to have eight plates. The outside end of the wire of the coil E, on a radial extension near one end of the body or core, is connected to the inner end of the coil E' on 90 the nearest radial extension, which is arranged in line with it lengthwise of the body or core. The outer end of the coil E' is connected to the inner end of the coil E², and so on to the last coil, E⁷, of the row. The outer end of the coil 95 E⁷ is connected by what I term a "loop," c, to the inner end of the adjacent coil, E⁸, of the next longitudinal row. The coils in this row are suc-

cessively connected, as before, to and including the last coil, E^{15} , of the row. The outer end of the coil E^{15} is connected by a loop, c' , to the inner end of the adjacent coil, E^{16} , of the next longitudinal row. The coils in this row are similarly connected, and the outer end of the last coil, E^{23} , is connected by a loop, c^2 , to the inner end of the adjacent coil, E^{24} , of the next longitudinal row. The coils of the last-named row are similarly connected, and the outer end of the last coil, E^{31} , is connected by a loop, c^3 , to the inner end of the adjacent coil of the next longitudinal row. The coils in that row are connected as before, and the last coil, E^{39} , of the row. The outer end of this coil E^{39} is connected by a loop, c^4 , to the inner end of the adjacent coil of the next longitudinal row. The remaining coils are similarly connected to and including the coil E^{63} , which is adjacent to the coil E . The outer end of the coil E^{63} is connected by a loop, c^7 , to the inner end of the coil E .

Leading-wires $d d' d^2 d^3 d^4 d^5 d^6 d^7$ extend from the loops $c c' c^2 c^3 c^4 c^5 c^6 c^7$ to the plates $e e' e^2 e^3 e^4 e^5 e^6 e^7$ of the commutator F . Brushes G , of ordinary or other suitable form, are used in connection with the commutator.

In the armature shown in Fig. 3 the outer end of one coil, E , is connected by a loop, c , to the inner end of the coil E^{15} next to it circumferentially of the body or core of the armature, and the outer end of the coil E^{15} is connected by a loop, c' , to the inner end of the adjacent coil, E^{16} . The coils are connected throughout the armature in circumferential rows by loops $c c'$, &c., as indicated in said figure, and leading-wires $d d'$, &c., extend from said loops to plates e of commutators F , one commutator being provided for each circumferential row of coils. In the rotation of this armature eight separate electric currents

will be generated. Brushes are to be provided for each commutator. The brushes of these commutators may be connected for either quantity or intensity, as may be desired.

I have not attempted to explain all the ways in which the coils on the radial extensions of the armature may be connected, as these ways are almost illimitable and will suggest themselves to those skilled in the art to which these improvements appertain after the few examples of different connections I have given. I desire, however, to remark, further, that the coils on the radial extensions may themselves be connected either for quantity or intensity.

What I claim as my invention, and desire to secure by Letters Patent, is—

1. An armature for a dynamo or magneto electric machine, composed of a hollow cylindric core, with openings at the ends for the admission of air, and radial extensions communicating at the inner ends with the interior of the body or core, open at the outer ends, and furnished externally with connected coils of wire, substantially as specified.

2. An armature composed of a hollow body or core, disks or end plates provided with openings for the entrance of air to the body or core, and tubular radial extensions furnished with connected coils of wire, substantially as specified.

3. The combination, with an armature composed of a hollow body or core and hollow radial extensions wound with wire, of one or more commutators connected with said coils of wire, substantially as specified.

CHARLES A. HUSSEY.
